UNITED STATES PATENT OFFICE

SYLVIAN G. KINDALL, OF FORT MONMOUTH, NEW JERSEY

HAT

Application filed August 3, 1931. Serial No. 554,860.

This invention relates to apparel and more particularly to a hat intended for use during fair weather.

One object of the invention is to provide a hat so constructed that a person's hair will be exposed to air and sunshine thereby preventing the head from becoming overheated due to being enclosed within the crown of a hat and also permitting rays from the sun to strike the hair and scalp.

Another object of the invention is to provide a hat including a shield which may serve as a wind deflector and will normally remain in an upright position about the back and sides of a person's head but may be drawn forwardly and secured in covering relation to the top of a person's head and prevent the hair from getting wet if a person is caught out during a rain storm.

Another object of the invention is to provide a hat which may be formed from a flat blank properly folded thereby permitting the hat to be very easily washed and ironed if it becomes soiled.

Another object of the invention is to so form the hat that the lining which is secured against the front face of the shield may have its lower portion extended downwardly and form a mantle serving to protect the back of a person's neck and also the shoulders if so desired and thereby prevent the neck and shoulders from becoming blistered by the sun.

Another object of the invention is to form the hat with a head encircling band extending across the bottom of the shield and having extended end portions adapted to be secured in overlapping and telescoping engagement with each other thereby permitting the band to accommodate itself to the circumference of a person's head and firmly hold the hat in place.

The invention is illustrated in the accompanying drawing wherein:

Figure 1 is a view in side elevation showing the improved hat in place upon a person's head, the position assumed by the shield when folded downwardly to cover the top of a person's head being indicated by dotted lines.

Figure 2 is a perspective view of the improved hat, this view showing the lining extending downwardly to form a neck protecting mantle.

Figure 3 is a view showing the hat in a flattened condition and the lining partially broken away.

Figure 4 is a sectional view taken vertically through the hat.

Figure 5 is a sectional view taken horizontally through the forward portion of the head encircling band along the line 5-5 of Figure 2, and

Figure 6 is a fragmentary view showing a portion of the shield and one end portion of the head encircling band.

The improved hat is preferably formed of fabric which may be water-proofed if so desired, but should be thin enough to permit it to be easily washed and ironed. The blank 1 is triangular in shape as shown in Figure 3 and has the upper portion of its front face covered by a lining 2 which may be formed of the same kind of fabric used for the blank 1 or may be of a different color or type of fabric.

The lining conforms to the shape of the upper portion of the blank which forms the shield when the blank is folded and in order to stiffen the shield and cause it to remain in an upright position when the hat is worn, there is employed a stiffening sheet 4 which may be formed of cardboard or a stiff fabric.

While the sheet 4 must have sufficient stiffness to normally retain the shield in an upright position when the hat is worn as shown in Figure 1 it must be sufficiently flexible to permit the shield to be drawn forwardly as indicated by dotted lines in this figure and serve to cover the top of the head and thereby prevent a person's hair from becoming wet if a person is caught out during a rain storm.

If so desired the lining 2 may be of greater depth as shown in Figure 2 and have its lower portion free from the blank 1 thereby permitting this lower portion of the lining to extend downwardly and form a mantle 5 adapted to protect a person's neck and prevent the same from becoming blistered by the sun. It is well known that many persons are

often made sick by sun shining upon the back of the neck. This mantle may be of sufficient size to only shield the neck or it may be of sufficient size to cover both the neck and shoulders and prevent the shoulders from becoming blistered when wearing a bathing suit.

After the reinforcing sheet and the lining have been applied and secured by stitching passed through marginal portions of the lining, the lower portion of the blank 1 is folded upwardly upon itself along the dotted folding lines 6 thereby forming a band 7 which extends across the outer face of the base of the shield and has its end portions 7' projecting from opposite sides of the base. It should be noted that the lining 2 is not secured to the blank along its lower edge and therefore the stiffening sheet may be withdrawn when it is necessary to wash the hat and then replaced after the hat has been ironed. The band 7 is in the form of a flat tube which has open ends as shown at 8 in Figure 6 and the extreme end portions of the band form tongues 9. By this arrangement the end portions of the band 25 may be disposed in overlapped relation to each other and the tongues 9 tucked into the open ends 8 of the band.

Therefore the extended ends of the band may not only be overlapped but disposed in telescoping relation to each other and the forward portion of the band which extends across a person's forehead when the hat is worn may be adjusted in order to cause the band to fit snugly about a person's head and retain the hat in place. After the telescoping ends of the band have been properly adjusted, a fastener 10 which may have an ornamental head and is provided with a pair of prongs 11 is passed through the overlapped tongues 9 and by spreading the prongs as shown in Figure 5, the overlapped ends of the band will be firmly secured in an adjusted position. In view of the fact that the prongs make very small openings when passed through the overlapped end portions of the band it may be removed and the band adjusted when necessary without the appearance of the band being marred as would be the case if the fastener required larger openings.

If a person is caught out during a rain storm, the upper end of the shield may be drawn forwardly and held in position to cover the top of a person's head by passing the prongs of the fastener 10 through the pointed end of the shield.

What is claimed is:

1. A hat comprising a head encircling band, and a shield extending upwardly from the band for a portion of the circumference thereof and adapted to fit about the rear and side portions of a person's head and extending upwardly above a person's head, and a lining for said shield secured in covering relation to the front face thereof and extended to form a mantle projecting downwardly from the rear

portion of said band beneath said shield to protect a person's neck.

2. A hat comprising a head encircling band, and a shield extending upwardly from the band for a portion of the circumference thereof and adapted to fit about the rear and side portions of a person's head and extending upwardly above a person's head, a lining for said shield secured in covering relation to the front face thereof, and a stiffening sheet for said shield disposed between the shield and lining and serving to retain the shield in an upright position, said sheet being sufficiently flexible to permit the shield to be folded forwardly and releasably secured to the band and cover the top of a person's head.

3. A hat comprising a shield, and a head encircling band extending across the bottom of said shield with its ends projecting from opposite sides thereof, a lining covering the front face of said shield and extended downwardly beneath the band to form a mantle, a stiffening sheet between the shield and lining, the shield being bowed transversely to fit against the back and side portions of a person's head and the band having its end portions brought forwardly and disposed in telescoping engagement with each other across a person's forehead, and a fastener to releasably secure the end portions of the band overlapped.

4. A hat comprising a substantially triangular shaped blank the upper portion of which constitutes a shield, said blank having its lower portion folded upwardly upon itself to form a flat tubular band extending across the lower portion of the shield and projecting from opposite sides thereof, the shield being bowed transversely and the extended end portions of said band being overlapped and disposed in telescoping engagement with each other, and means to releasably secure the end portions of the band in engagement with each other.

5. A hat comprising a blank reduced in width towards its upper end and having its lower portion folded upwardly upon itself to form a shield having a flat tubular band extending across its lower portion and projecting from opposite sides of the shield, a lining for said shield secured against the opposite face thereof from said band, a stiffening sheet between the shield and lining, said shield being bowed transversely to fit about the back and sides of a person's head and the extended ends of the band being brought forwardly and disposed in overlapped and telescoping engagement with each other, and a fastener passed through the overlapped portions of said band to releasably secure the same in an adjusted position.

6. A hat comprising a head encircling band, a substantially triangular shield projecting upwardly from a portion of the band and adapted to be folded downwardly over

the head with the apex of the shield secured to another portion of the band, and a lining for the shield having its lower portion extended downwardly beneath the band to form
5 a neck protecting mantle.

7. A hat comprising a tubular head encircling band having its ends provided with tongues overlapping and fitting within the band, a substantially triangular shaped
10 shield projecting upwardly from one portion of the band and adapted to normally extend above the top of a person's head and be folded downwardly with its apex bearing against another portion of the band, and a fastening
15 device extending through the tongues and the apex of the shield for securing the ends of the bands together and the shield in covering relation to the head.

In testimony whereof I affix my signature.
